UNITED STATES PATENT OFFICE.

ADOLPH PETZOLD, OF PHILADELPHIA, PENNSYLVANIA, ASSIGNOR TO JOHN H. BROMLEY AND EDWARD BROMLEY, COPARTNERS TRADING AS JOHN BROMLEY & SONS, OF PHILADELPHIA, PENNSYLVANIA.

DESIGN FOR A RUG.

45,952.

Specification for Design. Patented June 16, 1914.

Application filed April 29, 1914. Serial No. 835,313. Term of patent 7 years.

To all whom it may concern:

Be it known that I, ADOLPH PETZOLD, a citizen of the United States, residing in the city of Philadelphia, State of Pennsylvania, have invented a certain new, original, and ornamental Design for Rugs, of which the following is a specification, reference being had to the accompanying drawing, forming part thereof.

The figure is a quarter section of an Ax-minster rug, the other three quarter sections being identical therewith, showing my new design.

I claim:—

The ornamental design for a rug, as shown.

ADOLPH PETZOLD.
